(57) **CLAIM**

An ornamental design for a shaped ice mold, as shown and described.

DESCRIPTION

FIG. 1 is a top isometric view of a shaped ice mold showing our new design.

FIG. 2 is a right side view thereof.

FIG. 3 is a left side view thereof.

FIG. 4 is a front view thereof.

FIG. 5 is a rear view thereof.

FIG. 6 is a top view thereof; and,

FIG. 7 is a bottom view thereof.

The broken line showing of the surface features is included for the purpose of illustrating portions of the shaped ice mold and forms no part of the claimed design.

The present invention relates in general to beverage containers and, in particular, to an insulated beverage container.
